MEDICAL SYRINGE

Filed Dec. 29, 1944

Inventor

SAMUEL JAMES EVERETT,

By

Robert B. Parsons

Attorney

end with a slight taper and the interior of the metal ring is formed with a corresponding taper, the ring being shrunk directly on to the cylinder.

I claim:

1. A medical syringe comprising a glass barrel, a technical porcelain front closure member having an integral nozzle portion at one end, the other end of said porcelain closure member extending into and in sliding contact with the front end of said barrel, said front closure member having substantially the same coefficient of expansion as said glass barrel, and a metal ring disposed on the barrel and adjacent the front end thereof for clamping said barrel to said front closure member, said metal ring having an internal diameter less than the normal external diameter of said glass barrel, the front part of said barrel being thus compressed by said ring into clamping engagement with said closure member.

2. A medical syringe comprising a glass barrel, a technical porcelain front closure member having an integral nozzle portion at one end, the other end of said porcelain closure member extending into and in sliding contact with the front end of said barrel, said front closure member having substantially the same coefficient of expansion as said glass barrel, and a metal ring

shrunk on the barrel and adjacent the front end for clamping said barrel to said front closure member, said metal ring having an internal diameter less than the normal external diameter of said glass barrel, the front part of said barrel being thus compressed by said ring into clamping engagement with said closure member.

SAMUEL JAMES EVERETT.
